UNITED STATES PATENT OFFICE.

JOHN W. DODD, OF BROOKLINE, MASSACHUSETTS, ASSIGNOR TO GEORGE T. McLAUTHLIN COMPANY, OF BOSTON, MASSACHUSETTS, A CORPORATION OF RHODE ISLAND.

DOOR LOCK.

Application filed November 12, 1926. Serial No. 147,924.

This invention relates to door locks, more particularly intended for use in connection with the doors of elevator shafts, though certain features of the invention might be applicable to doors in other locations. In order to prevent accidents the doors leading to an elevator shaft normally should be shut and locked except when the elevator car is stationary opposite a door opening, whereupon the door for that opening only should be releasable so that it may be opened. It should, however, be possible for an authorized person, such as an inspector or repairman, to have access to the shaft through a door opening quite regardless of the position of the car. A lock particularly designed to accomplish these ends is disclosed and claimed in Patent No. 1,595,559 granted to Martin B. McLaughlin on August 10, 1926, for elevator shaft door lock.

The present invention in certain respects is an improvement over the McLaughlin construction. One of the objects of the present invention is to simplify the lock construction, rendering it more rugged and avoiding the necessity of using springs.

A further object is to provide such a lock readily adaptable to either right hand or left hand sliding or swinging doors.

30 A still further object is to provide such a lock wherein the parts may be assembled or an assembly already made may be readily changed to meet the particular changes presented in the various door arrangements and without the use of special tools.

For a more complete understanding of this invention, reference may be had to the accompanying drawings in which:—

40 Figure 1 is a fragmentary vertical section through an elevator shaft showing in elevation a locking mechanism in connection with a sliding door.

45 Figure 2 is a vertical section at right angles to Figure 1 and showing a portion of the elevator car.

Figure 3 is a view similar to Figure 2, but showing the application of a mechanism in connection with a swinging door.

50 Figure 4 is a view to a larger scale of a portion of the mechanism, the cover plate being removed.

Figure 5 is a view similar to Figure 4 but showing the parts in door released position.

55 Figure 6 is a section on line 6—6 of Figure 5.

Figure 7 is a fragmentary view similar to a portion of Figure 5 but showing the positions of the parts when the door handle or knob is turned and the car is not opposite the door opening.

60 Figure 8 is a detail section on line 8—8 of Figure 4.

Figure 9 is an elevation of the latch plate secured to the door.

65 Figure 10 is a view somewhat similar to Figure 1, but showing a door movable in the opposite direction to open and close from that shown in Figure 1.

Figure 11 is a vertical section at right angles to Figure 10.

70 Figure 12 is an elevation somewhat similar to Figure 4 but arranged for a sliding door closing in the opposite direction and showing a modified form of door contact member.

Figure 13 is a fragmentary section on line 75 13—13 of Figure 12.

Figure 14 is a detail section on line 14—14 of Figure 7.

Figure 15 is a view somewhat similar to Figure 4 but with certain parts differently 80 connected.

Figure 16 is a detail perspective.

Figure 17 is a horizontal section through a portion of the elevator shaft showing the key release mechanism for use with a sliding 85 door.

Figure 18 is a detail elevation showing a portion of the same mechanism.

Referring first to Figures 1 and 2, at 1 is shown a door for closing a door opening to 90 an elevator shaft, portions of the frame of this doorway being shown at 2 and 3. A portion of a car in said shaft is shown at 4. The

shaft door 1 is shown in these figures as a sliding door moving between spaced guides 5 and 6 carried by the door casing member 2. To the casing member 3 of this doorway is attached, as by brackets 8 and 9, a casing 10 which contains certain movable parts of the locking mechanism which will be hereinafter described. This casing has a normally open side at 11, and a cover 12 closes this side when the door is closed, this cover 12 being carried by the door, a suitable bracket member 13 fixed to the inner face of the door being shown as supporting this cover in position. Beneath the casing 10 the door 1 is shown as provided with a rock shaft 15 extending therethrough and having a knob 16 fixed to its outer end on the outside of the door by which 110

it may be turned. A similar knob 17 is shown as fixed at the inner end of this shaft 15 but this may be omitted if desired. Carried by the rock shaft 15, as shown best in Figure 1, is a rock arm 18 supported within a box element or housing 19, and extending into this housing, resting on the end portion of the arm 18 is the lower end of a plunger rod 20 slidably guided for axial vertical movement through the guide shown at 21 carried by the door. The upper end of this plunger rod is guided through an opening 22 in the inwardly turned lower end 23 of the cover 12, this being shown in Figures 4 and 5. The arm 18 is normally held in substantially horizontal position by any suitable means, but may be rocked upwardly by manipulation of either of the knobs 16 or 17 to raise the plunger for a purpose which will later appear.

Referring now to Figures 4, 5, 6 and 8, it will be seen that the casing 10 comprises a frame portion having an upper wall 25, a vertical end wall 26 opposite to the open side 11 and a bottom short wall portion 27 toward which the inturned portion 23 of the cover 12 approaches when the cover is in door closed position. Opposite sides of the frame member comprising these three walls may be closed off by means of removable cover plates 30 and 31. These cover plates are interchangeably engageable on opposite sides of the frame for a purpose which will later appear. They may be fixed in place by suitable means such as screws as shown at 35 in Figure 1, these screws being threaded into the frame. Certain of the screw openings in the frame may extend entirely through the frame, as shown for example at 37 and these are countersunk on both sides of the frame and are intended to receive long bolts which may extend therethrough and fix the casing to the shaft with certain door arrangements, this however being unnecessary when the casing is mounted for a sliding door as shown in Figure 1. These screw holes at 37 are countersunk at opposite sides so that the casing may be fixed either side out with the covers 30 and 31 interchanged as will later appear. The frame wall 26 is provided with an inwardly extending lug 40 on opposite sides of which is pivoted through spaced bosses 41 thereon a latch member 42 having a latch lip 43 adjacent to its free end. This latch member is preferably formed somewhat box shaped with a stiffening rib 44 extending thereacross. At opposite sides this latch member is shown as provided with downwardly extending flanges 45 and 46. Between these flanges is passed a pivot pin 47 on which is pivoted a guide rod 48. The lower end of this rod is formed of circular cross section as at 49 and is slidably guided through either one of a pair of holes 50 in the wall member 27, this being shown best in Figure 16. The pivot 47 comprises a straight pin or bar of uniform diameter

throughout which extends through the flanges 45 and 46 and is held assembled therein by means of the cover members 30 and 31 of the casing between which it wholly lies, being held against undue endwise movement by engagement of its ends with the inner flat faces of the cover members between which it has floating bodily movement having no fixed supports. The casing walls, therefore, act to restrain this pin against undue endwise movement only. The casing walls and the elements pivotally connected are thus the only portions of the lock with which the pivots contact. The member 48 is provided on one side with a lug 52 which extends within a socket portion 53 in a bell crank lever 54, this lug being pivoted within the socket portion on a pin 55 passing therethrough. This pin 55 also preferably extends adjacent to and is held in assembled position with relation to the bell crank lever and the lug 52 by the cover plates 30 and 31, similarly to the pivot pin 47. One arm of this bell crank lever 54 is formed elongated as at 56, this elongated portion being perforated for the reception of a pivot pin 57 on which is suspended an abutment member 58, this member being shown as formed U shape, the pivot passing through the end portions of its oppositely disposed arms, and its central transversely extending portion 59 being positioned above the upper end of the plunger rod 20 when the door is in closed position.

When the door is a sliding door, as shown in Figures 1 and 2, the casing also carries journaled in the wall 26 a rock shaft 60. This rock shaft extends adjacent to the upstanding end wall 61 of the wall portion 27 and is prevented from endwise movement in one direction by this end wall. It has pinned thereto adjacent to a bearing boss 63 on the wall 26 through which it passes, a collar 64 which prevents endwise motion of this shaft in the opposite direction. This collar is extended on one side and has a pin 65 extending therefrom which projects between a pair of pins 66 fixed to a rock arm 67 journaled on a pivot shaft 68 fixed to an ear 69 integral with the walls 26 and 27 at their adjoining corner. This rock arm 67 has pivoted at its upper end a pair of links 70 pivoted on pin 71, these links also passing one on each side of the guide rod 48 and being pivoted at 72 to another arm 73 of the bell crank lever 54.

Outwardly of the casing 10 the rock shaft 60 has fixed thereto an arm 73 to the free end of which is fixed a suitable element which may be projected into the path of movement of the car when the car is not in position opposite to the doorway and which will be stopped by impingement on a portion of the car should it be opposite to the doorway whenever the rock shaft 60 is rocked in the proper direction. The cover member 12 is provided with a latch element 80 having an

upturned hooked extremity 81 engaging behind the latch lip 43 when the door is in closed position. The pivot pin 72 is shown as comprising a cylindrical rod of sufficient length 5 to extend across the casing and to be held in position by the cover members 30 and 31 similarly to the pins 47 and 55, while the pivot 71 is shown as comprising a headed pin having a cotter pin extending through a perforation at its small end to hold it in position. It has been found desirable to form the pivot pin for one end of the links in this manner 10 to hold the links in proper position. Either end of the links may be so held, one being sufficient.

Assume now that the door is closed and that the car is not opposite the doorway. If, under these conditions, the knob 16 be turned to raise the plunger rod 20 the upper end of this rod 20 contacts on the abutment member 58, this 25 rocking the bell crank lever 54 about its fulcrum 55, this through the links 70 rocking the arm 67 and through the engagement of the pin 66 thereon with the pin 65 on the collar 64, rocking the shaft 60 to bring the free 30 end of the arm 75 toward the path of motion of the car. The car not being positioned opposite the doorway there is nothing to stop the continued motion of the arm and the parts 35 continue to move as thus described until the stop collar 85 on the plunger rod strikes the portion 22 and stops further movement. If a car be positioned opposite the doorway when the knob 16 is turned, the arm 75 rocks 40 until further motion is prevented by contact of the arm 75 on a portion of the car. Further upward motion of the plunger then causes the bell crank lever 54 to move upward bodily, the links 70 rocking about their pivotal connection with the arm 67. This raises the lug 52, raising the guide rod 48 and lifting the latch member 42, thus freeing the latch element 80 therefrom, whereupon the door may be opened.

45 In most cases it is desirable that unlocking of the door by actuation of the knob be prevented when the car is in motion even though it may be opposite the doorway. For this reason the free end of the arm 75 may have fixed thereto a rock arm 90 normally held with its end projecting outwardly and maintained substantially horizontal by means of a spring 91. When the end of this arm 90 is thrown 50 toward the path of the car and contacts with a stationary part as 91 thereon further motion of the arm 75 is prevented, but if the car should be moving such motion causes the arm 90 to be turned out of its normal horizontal position, whereupon motion of the arm 75 55 may be continued the arm 90 rocking toward parallelism with the arm 75 so that the door will not be released. This particular contact mechanism is more particularly disclosed and claimed in the McLauthlin patent hereinbefore referred to.

Where it is not desired to cause motion of the car to prevent unlocking of the door any suitable contact means such as a roller, as shown as 93 in Figures 13 and 14 may be substituted for the arm 90.

70 In Figures 3, 7 and 14 the mechanism is shown as applied to a swinging door, the door being indicated at 100. In this case the casing 10 is fixed to the door casing by screws passing through the casing frame at 37, the wall member 31 being interposed between the edge of this casing frame and the elevator shaft member. The rock shaft as 166 is then arranged to project through an opening in the opposite cover member 30, being arranged at 80 right angles to the position of the rock shaft 60 shown in Figures 4 and 5. As shown in Figure 14 it is journaled through this cover 30 and through the car 102 extending across between the wall members 26 and 27 opposite 85 to the wall member 69. The rock arm 67 is then fixed directly to this rock shaft and a collar 103 is interposed between this arm 67 and the ear 69 to hold the parts from axial movement.

90 The motion of the arm 75 is thus at right angles to its motion when the casing is mounted as shown in Figure 1 and as the casing is mounted at right angles to its former position relative to the elevator shaft the arm 75 95 carried by this rock shaft is in proper relation to cooperate with the elevator car as shown in Figure 3. The action of the device is the same as before, rocking of the knob 105 on the outside of the pivotal door when this door 100 is closed, raising the plunger rod, contacting with the abutment member 58 within the casing, and rocking the arm 75 until such motion is stopped by the car if the car is positioned opposite the doorway and being uninterrupted for the full travel of the plunger rod 105 in case the car is not so positioned. In case the car is so positioned the rocking of this arm 75 is stopped and motion thereafter raises the bell crank lever and, consequently the latch 110 member, to release the latch element carried by the shaft door.

115 Where the door is pivoted to swing in the opposite direction it is necessary to reverse the side of the casing which is attached to the elevator shaft wall, the cover plates 30 and 31 being then interchanged so that the cover plate 31 is adjacent to the shaft casing, so that the rock shaft may extend outwardly 120 therefrom through the opening in the opposite cover 30. As this direction to which the shaft extends determines the side of the casing to which the arm 67 is most nearly adjacent where such changes are made, it is necessary to change the position of the rod 48 125 from one to the other of the holes 50, the other parts being moved over correspondingly.

130 Where the door is a sliding door and moves oppositely to that shown in Figures 1 and 2 it is necessary to fix the casing to the oppo-

site side of the doorway from that shown in Figure 1, the rock shaft 60 then being positioned on the opposite side of the rock arm 67 and through the opening shown at 600 (Figures 6 and 16).

Since the arm 75 is fixed adjacent to the side of the doorway toward which the door closes, the showing of Figures 1, 2, 4, 5 and 6 would be reversed as in Figures 12 and 13 10 when the door closes in the opposite direction, so that if the shaft 60 and the arm 75 were left in the same relationship as shown in Figure 1, they would be rocked in the wrong direction by turning of the knob. When the 15 parts are positioned for door moving in reverse direction to that shown by Figure 1, therefore the rock shaft 60 is arranged as shown in Figures 12 and 13 on the opposite side of the rock arm 67 with the pin 65 engaging 20 between the opposite ends of the pins 66, so that the direction of motion of the arm 75 is as it should be, and the spacing from the door of the rock shaft 60 carrying the arm 75, is the same as in the arrangement shown in Figure 25 1.

In some cases it may be desirable to have the arm 75 extend downwardly instead of upwardly and for this reason the bell crank lever 54 has been shown with an extension 30 beneath the socket portion 53 as at 110, this extension being shown as provided with an opening 111 through which the pivot pin for the links 70 may be passed, as shown for example in Figure 15. Rocking of the bell 35 crank lever by raising of the abutment member 58 will thus act to move these links in the opposite direction, thus to rock the shaft 60 in the opposite direction so as to permit the arm 75 to move toward the car path by 40 the opposite direction of rocking.

It is also sometimes desirable that the electric current supply for the motor which actuates the car shall be interrupted when any of the doors are opened. Where this is desirable 45 a suitable switch mechanism may be provided. As shown this switch mechanism comprises a conducting plate 120 set in a block of insulation 121 carried on the door cover 12, this when the door is closed and 50 locked bridging a pair of spring contact members 122. These members 122 are shown as supported on pins 123, these pins being surrounded by springs 124 bearing on the contact members and holding them in close engagement 55 with the terminal strips 125 to which the power cables 126 are attached. The spring contacts 122 are shown as provided with downward bends 127 which are contacted by and raised when the latch member 42 is raised to release the door. Thus 60 the electrical connection between the contacts 122 through the bridge member 120 is broken so that current can no longer pass. It will be seen that for the latch mechanism 65 itself no springs are required to hold the

parts in operative relation, all the mechanisms acting by gravity and that whenever the knob is turned the door may not be released unless the car is in proper position opposite the doorway.

While it is not desirable that the door should be openable under normal conditions, except when the car is opposite the doorway, nevertheless, it is often desirable that an 70 inspector, repairman, or other qualified or authorized person, be able to open the door at any time. A mechanism suitable for actuation to release the door at any time when the door is mounted to slide is shown in Figures 17 and 18.

Referring to these figures it will be seen that the latch element 80 has a lateral perforation wherein is journaled a rock shaft 150. Fixed to the inner end of this rock shaft is a latch release finger 151, having its free end 85 extending beneath the latch lip 43, a stop pin 152 fixed to the element 80, preventing the finger from dropping to vertical position. The opposite end of rock shaft 150 extends into a hole 155 through the door 1, and is 90 squared or otherwise formed for engagement by a key 156 with which a person authorized to open the door at any time is provided. By means of this key the rock shaft 150 may be turned to cause the release finger 151 to raise 95 the latch so as to release the door at any time regardless of the position of the car.

Where the door is mounted to swing, it may be provided with a perforation registering with a perforation 160 (Figure 7) through 100 the cover member 12, so that a beveled ended releasing member, shown dotted at 161, may be passed therethrough and pushed under the latch lip 43, to raise the latch member and thus release the door.

While the casing 10 is shown as provided with various holes through which parts may be passed selectively, depending upon the door mounting, where the particular door mounting for which an installation as intended is known, the mechanism may be made up for that mounting alone, thus saving the labor of forming the holes which will not be required and perhaps improving the appearance of the mechanism as installed. The 110 same general mechanism is, however, readily adapted to various door mountings by a simple rearrangement of parts, so that manufacturing costs are reduced.

Having thus described an embodiment of 120 this invention it should be evident to those skilled in the art that various changes and modifications might be made without departing from its spirit or scope as defined by the appended claims.

I claim:

1. In combination, a casing comprising 130 walls and a latch pivoted in said casing, and mechanism actuatable under certain conditions only to move said latch, said mechanism com-

- prising pivotally connected elements, the pivots for certain of said elements being bodily movable with reference to said casing and comprising rods lying entirely between 5 said walls and retained in position thereby.
2. In combination with a shaft having a door opening, a door for closing said opening, and a car in said shaft, of a casing, a latch member in said casing, a latch member 10 on said door, means for fixing said casing to said shaft in any of a plurality of relations to permit cooperation of said latch members to hold the door closed whether said door be mounted to swing or slide, a rock shaft mounted 15 in said casing and extending outwardly thereof in any selected one of a plurality of directions, the direction selected being in accordance with the mounting of said casing relative to said shaft, a lever fixed to the projecting 20 portion of said rock shaft being movable toward and from the path of said car as said shaft is rocked, and means actuatable when said door is closed to rock said shaft to bring the free end of said lever toward said path 25 when said car is not opposite to said doorway, and to bring said free end toward said car to be stopped thereby and thereafter to release said latch members when the car is opposite to said doorway.
3. The combination with a shaft having a doorway, and a door for closing said doorway, a casing for attachment to said shaft, said casing having an open side, a latch member in said casing, a cover for attachment to said 30 door, said cover bridging said open side when said door is closed and having a latch element engaging said latch member when said door is closed for holding said door closed, a rock shaft extending outside of said casing, an 35 arm fulcrumed within said casing, operative connections between said arm and shaft whereby rocking of said arm rocks said shaft, a lever pivotally connected to said latch member, a link connecting said arm and lever, and a member movable relatively to said 40 cover and operatively related to said lever to rock said lever and thus rock said rock shaft when said rock shaft is permitted to rock, and to move said lever bodily to release 45 said latch members when said rock shaft is held from rocking.
4. The combination with a shaft having a doorway, a door for closing said doorway, and a car in said shaft, of a casing fixed to said 50 shaft, a rock shaft carried by said casing, an arm on said rock shaft having its free end movable toward and from the path of said car, a latch member pivoted in said casing, a latch element carried by said door and co- 55 operating with said latch member when said 60 door is closed to hold said door closed, a rod pivoted to said latch and slidably guided in said casing, a bell crank lever pivoted to said rod, and an abutment member pivotally suspended from one arm of said bell crank lever, 65 a rock arm operatively related to said rock shaft, a link connecting said arm to the other arm of said lever, a plunger slidably carried by said door in position to strike and raise said abutment member when said door is 70 closed, the raising of said abutment acting to swing said shaft arm when said car is not opposite to said doorway and acting to release said latch member when said car is opposite to said doorway, and means accessible 75 externally of said door for raising said sliding plunger to impinge on and raise said abutment member.
5. The combination with a shaft having a doorway, a door for closing said doorway, 80 and a car in said shaft, of a casing fixed to said shaft, a rock shaft carried by said casing, an arm on said rock shaft having its free end movable toward and from the path of said car, a latch member pivoted in said casing, a latch element carried by said door and cooperating with said latch member when 85 said door is closed to hold said door closed, a rod pivoted to said latch and slidably guided in said casing, a bell crank lever pivoted to 90 said rod, and an abutment member pivotally suspended from one arm of said bell crank lever, a rock arm operatively related to said rock shaft, a link connecting said rock arm to the other arm of said bell crank lever, a 95 plunger slidably carried by said door in position to strike and raise said abutment member when said door is closed, the raising of said abutment acting to swing said shaft arm when said car is not opposite to said doorway and acting to release said latch member when said car is opposite to said doorway, said door having an opening through which a latch releasing member may be passed from outside of said shaft and into position to release 100 said latch member from said element.
6. A device of the class described comprising, in combination, a casing, a latch carried by said casing, and mechanism actuatable to move said latch comprising pivotally connected elements, said casing having opposed walls at opposite ends of certain of the pivots of said elements retaining said pivots against undue endwise motion only and with said elements constituting the sole portions of 110 said device with which said pivots contact.
- In testimony whereof I have affixed my signature.

JOHN W. DODD.
